(57) **CLAIM**

The ornamental design for an eyeglass display, as shown and described.

DESCRIPTION

FIG. 1 is a perspective view of an eyeglass display in accordance with a preferred embodiment of the present invention;

FIG. 2 is a front elevational view of the eyeglass display as shown in FIG. 1;

FIG. 3 is a right side elevational view of the eyeglass display shown in FIG 1, with the left side view being a mirror image thereof;

FIG. 4 is a top plan view of the eyeglass display shown in FIG 1;

FIG. 5 is a back elevational view of the eyeglass display as shown in FIG. 1; and,

FIG. 6 is a bottom plan view of the eyeglass display as shown in FIG. 1.

The broken lines are for illustrative purposes only and form no part of the claimed design.

The wavy line in FIGS. 3, 4, and 6 depicts a cutaway portion and forms no part of the claimed design.
